SUCTION HORN

Application filed January 26, 1932. Serial No. 588,899.

This invention relates to pneumatic horns as principally used for automobiles, and has for its object an improved construction in suction-operated horns whereby a better note with less vacuum is obtained, and also which will provide externally accessible means for manually adjusting the note. Another feature is an extreme compactness of design so as to take up little space. Other features of advantage will appear in the following description and accompanying drawing.

In the drawing Fig. 1 is a side elevation of the complete horn.

Fig. 2 is an enlarged cross section of the horn as seen from the line 2—2 of Fig. 1.

Fig. 3 is a detached view on one-half of the horn as seen from the line 3—3 of Fig. 2 to show its internal spiral shape.

Fig. 4 is a plan view of the valve attached to the center of the flexible diaphragm.

Fig. 5 is a perspective view of the ratchet washer controlling the tension adjustment.

Fig. 6 is an enlarged sectional view of the diaphragm valve.

In further detail the device comprises a horn made of two sections 1, 1' bolted or otherwise secured together as at 3. The complementary halves of the horn are preferably spirally shaped as shown in Fig. 3 with a gradually increasing size sound and air passage 4 terminating outwardly in a flared open end 4', and inwardly making a right angle turn 5 communicating with a circular cavity or chamber 6 formed centrally in the outer side of section 1 and over which cavity is bolted, or otherwise secured, a bonnet member 7 formed with a coinciding circular cavity 8 and between which bonnet and horn member 1 is clamped a soft flexible diaphragm 9 preferably made of textile material such as airplane cloth, or otherwise rendered non-porous as by oil treating or varnishing, or the diaphragm may be of thin flexible leather so treated.

Attached to the center of this soft flexible diaphragm is a circular valve seat 10 as best shown in Fig. 6 and which comprises a round relatively large shallow cup with a hub 11 passing through the diaphragm and a securing flange 12 screwed over the hub or other-

wise secured thereto clamping the diaphragm tightly between the cup and the flange. The cup is drilled with several holes 13 and it is resiliently forced outward (away from the bonnet) by means of a light helically coiled wire compression spring 14 bearing at its small end against the flange or hub of the valve, while limiting the outward movement of the valve seat is a thin flat valve disk 15 preferably of non-metallic material such as bakelite, thin fiber sheet, or other slightly flexible though stiff substance, and which valve disk is of a size to lie against and overlap the rim 10 of the valve seat so as to close the same.

This disk 15 is secured to the end of a threaded rod or screw 16 which extends axially and freely through the central hub aperture 17 of the valve and threadedly through the outer wall 7' of the bonnet where it is provided with a thumb nut 18 to permit manual adjustment of the screw to move the disk 15 in or out for varying the adjustment of the parts and tension of spring 14, and therefore the note produced.

Surrounding this screw and within spring 14 is a helical compression spring 19 positioned in a central extension or bore 8' of recess 8 arranged to react between the hub of the valve and the bonnet, or rather a fluted washer 20 splined as at 21 to the screw and bearing against a similar fluted washer 22 firmly seated in the bonnet, so that as the screw is turned the washer 20 will snap over the flutes in the fixed washer 22 and then act as a detent to hold the screw in any position of adjustment.

From bore 8' extends a suction port 23 which is connected by a pipe or hose 24 with any suitable source of suction, such as an exhausted tank or the intake manifold of an internal combustion engine.

To secure the horn to the frame of an automobile or other support I provide one or more lugs 25 apertured as at 26 for bolting in place.

Within valve chamber 6 and extending entirely across the same at a point to clear the disk 15 at all times, is a wire screen air strainer disk 27 which may be sprung at its edges into a groove formed around the chamber as indicated.

If desired, this strainer may be omitted and the strainer placed further out in the horn air passage as at 28 in Fig. 3 wherein it is sprung into a groove 29 formed around the 5 walls of the passage, or both strainers may be used, the outer one of a coarser weave. The screen is important in keeping out dirt and bugs which might otherwise lodge between the disk 15 and the valve rim 10.

10 In operation, when a valve (not shown) is opened in suction pipe 24 so as to produce suction in chamber 8, its effect on the large diaphragm 9 is to pull it and its attached valve seat inwardly into the recess or chamber 8 of 15 the bonnet and thus "crack" the valve to destroy the vacuum by inrush of air through the horn so that the valve disk will at once reseat through force of spring 14. The employment of a fabric or the like diaphragm results in a 20 wobbling action to the diaphragm not obtained with stiff metallic diaphragms. Also a much more sensitive and easier action with a lower vacuum. This sensitive action is contributed to by having the valve disk 15 of 25 flexible non-metallic material as it provides a resilient seat for the valve so that it bounces open the moment it closes and thus sets up a high speed vibratory action and a piercing note.

30 The quality of the note may be changed by simply turning the thumb screw 18 and thereby putting more or less tension against the spring 14 and therefore affect its yielding to the suction applied to the inner surface of 35 the flexible diaphragm.

I am aware of similarly operated horns, but not with the soft diaphragm to induce wobble of the valve seat, nor of the external 40 adjustment feature, nor the use of a coiled horn in such a combination with the diaphragm against one side, nor the flexible non-metallic valve disk, or other features as claimed hereunder.

I claim:—

45 1. A horn having a sound passage formed at its inner end with an opening extending substantially at right angles to the axis of the sound passage, a flexible diaphragm secured across said opening and a valve opening in said diaphragm, means for closing said valve opening, and means for pneumatically moving said diaphragm for cracking the valve.

50 2. A horn having a sound passage formed at its inner end with an opening extending substantially at right angles to the axis of the sound passage, a flexible diaphragm secured across said opening and a valve opening in said diaphragm, means for closing said valve opening, means for pneumatically moving said diaphragm for cracking the valve, said diaphragm having substantially no restoring resiliency, and a spring arranged 55 to restore said diaphragm.

60 3. A horn having a sound passage formed

at its inner end with an opening extending substantially at right angles to the axis of the sound passage, a flexible diaphragm secured across said opening and a valve opening in said diaphragm, means for closing said valve opening, means for pneumatically moving said diaphragm for cracking the valve, said diaphragm having substantially no restoring resiliency, a spring arranged to restore said diaphragm, and means for limiting the return movement of said diaphragm.

65 4. A horn having a sound passage formed at its inner end with an opening extending substantially at right angles to the axis of the sound passage, a flexible diaphragm secured across said opening and a valve opening in said diaphragm, means for closing said valve opening, means for pneumatically moving said diaphragm for cracking the valve, said diaphragm having substantially no restoring resiliency, a spring arranged to restore said diaphragm, and means for limiting the return movement of said diaphragm accessible 70 at the outside of the horn for manual manipulation.

75 5. A horn having a spirally shaped sound passage formed at its inner end with an opening extending substantially at right angles to the axis of the sound passage, a flexible diaphragm secured across said opening and a valve opening in said diaphragm, means for closing said valve opening, and means for pneumatically moving said diaphragm for cracking the valve.

80 6. A horn body having a spirally shaped sound passage with its inner end extending substantially at right angles with the axis of the passage and opening into an enlarged chamber formed in the side of the horn body, a bonnet secured to the side of the horn body 85 over said chamber, a flexible diaphragm secured across the chamber between the bonnet and the horn body, a valve carried by the diaphragm forming an air passage through the diaphragm, a valve closure carried by a 90 stem projecting through said air passage, and means for adjusting the position of the valve closure.

95 7. A horn body having a spirally shaped sound passage with its inner end extending substantially at right angles with the axis of the passage and opening into an enlarged chamber formed in the side of the horn body, a bonnet secured to the side of the horn body 100 over said chamber, a flexible diaphragm secured across the chamber between the bonnet and the horn body, a valve carried by the diaphragm forming an air passage through the diaphragm, a valve closure carried by a 105 stem projecting through said air passage, and means for adjusting the position of the valve closure located at a point accessible for 110 manual manipulation.

115 8. A horn provided with an air chamber at its inner end, a diaphragm of soft material 120

secured across said chamber, a valve seat secured to the diaphragm and ported to pass air from one side to the other, a spring resiliently forcing said valve seat in one direction transversely of the plane of the diaphragm, a valve disk arranged to close against said seat, and means for causing an unbalanced air pressure on one side of said diaphragm to crack the seating of the valve disk.

10 9. A horn provided with an air chamber at its inner end, a diaphragm of soft material secured across said chamber, a valve seat secured to the diaphragm and ported to pass air from one side to the other, a spring resiliently forcing said valve seat in one direction transversely of the plane of the diaphragm, a valve disk arranged to close against said seat, a stem supporting said disk passing through said valve seat and provided 15 with means for adjusting the position of the disk, and means for causing an unbalanced air pressure on one side of said diaphragm to crack the seating of the valve disk.

10 10. In a structure as specified in claim 8, 25 said disk made of a thin sheet of resilient non-metallic material.

10 11. In a structure as specified in claim 8, 25 said disk made of a thin sheet of resilient bakelite material.

10 12. In a structure as specified in claim 9, 30 means for locking said stem in adjusted position.

10 13. In a structure as specified in claim 9, 35 means for locking said stem in adjusted position comprising a spring-actuated frictional detent surrounding said stem.

10 14. In a pneumatic horn of the character 40 described, a diaphragm provided with a central opening and valve seat therearound, valve means for closing the opening, and means supporting the members for relative wobbling motion of the seat and valve means 45 for opening and closing the valve, and means for disturbing the equilibrium of the air operative on the diaphragm to cause such wobbling of the valve.

10 15. In a structure as specified in claim 9, a 45 filter screen across the air chamber to the outer side of said disk.

10 16. In a structure as specified in claim 9, a 50 filter screen disk across the air chamber to the outer side of said disk seated at its edges in a groove formed in the wall of the chamber.

10 17. In a structure as specified in claim 8, 55 said valve seat comprising a shallow cup-like member with a central aperture and a plurality of apertures spaced around the central aperture.
